US00D751104S

(12) **United States Design Patent**
Chetan et al.

(10) **Patent No.:** **US D751,104 S**
(45) **Date of Patent:** **** Mar. 8, 2016**

(54) **DISPLAY SCREEN WITH GRAPHICAL USER INTERFACE**

(71) Applicant: **Microsoft Corporation**, Redmond, WA (US)

(72) Inventors: **Kishan S. Chetan**, Copenhagen (DK); **Jujhar Singh**, Clyde Hill, WA (US); **Ted Cyrek**, Sammamish, WA (US); **Nikola Jelisavac**, Copenhagen (DK)

(73) Assignee: **Microsoft Corporation**, Redmond, WA (US)

(**) Term: **14 Years**

(21) Appl. No.: **29/488,770**

(22) Filed: **Apr. 23, 2014**

(51) **LOC (10) Cl.** **14-04**
(52) **U.S. Cl.** USPC **D14/486**

(58) **Field of Classification Search**

USPC 715/712, 713, 733, 750, 751, 760, 764, 715/773, 810, 818, 825, 828, 14.41; D14/485-495

CPC . G06F 3/0482; G06F 3/04842; G06F 3/0481; H04N 1/00408-1/00437; G06Q 30/0242

(57) **CLAIM**

The ornamental design for a display screen with graphical user interface, as shown and described.

DESCRIPTION

The FIGURE is a front view of a display screen with graphical user interface showing our new design. The broken line showing of the text, the various icons, the remainder of the user interface and the remainder of the display screen is for environmental purposes only and forms no part of the claimed design.

1 Claim, 1 Drawing Sheet
